United States Patent Office.

GEORGE W. NEILL, OF BOSTON, MASSACHUSETTS.

Letters Patent No. 79,591, dated July 7, 1868.

IMPROVEMENT IN PIANO-FORTES.

The Schedule referred to in these Letters Patent and making part of the same.

TO ALL PERSONS TO WHOM THESE PRESENTS MAY COME:

Be it known that I, GEORGE W. NEILL, of Boston, in the county of Suffolk, and State of Massachusetts, have invented a new and useful Improvement in Piano-Fortes; and do hereby declare the same to be fully described in the following specification, and represented in the accompanying drawings, of which—

Figure 1 is a side elevation,

Figure 2 a vertical and transverse section, and

Figure 3 a horizontal section of the back frame, the sounding-board, and the metallic string-frame of an upright piano, as combined and arranged in accordance with my invention.

Figure 4 is a front elevation of the back frame.

Figure 5 is a front elevation of the main iron or string-frame.

Figure 6 is a front view of the sounding-board.

Figure 7 is a front elevation, and

Figure 8 an end view of the ordinary metallic frame.

In making my invention, I have had the following objects in view: First, to so construct the metallic frames for supporting the strings that its bars may not come between them, to interfere with any desirable arrangement of them; second, to cover from view the main portion or bars of the iron frame; third, to produce a very strong and durable support for the strings, and with the metal thereof so arranged, with respect to them, as to expand and contract uniformly therewith under ordinary changes of temperature, in order that the strings may be maintained at their proper tension, and the instrument thereby be preserved in good tune.

In carrying out my invention, I arrange the metallic or string-supporting frame A directly between the back frame B and the sounding-board C, the latter being in front of such metallic frame. Furthermore, I arrange an auxiliary metallic string-frame, D, in front of part of the sounding-board, and provide the auxiliary metallic frame with one or more lips, *m n*, at its outer edge or edges, to extend therefrom, and lap on and against the adjacent edge or edges of the main metallic frame.

The main iron frame A, I construct not only of top and bottom parallel rails or bars, *a a'*, and connection-bars, *b b b*, arranged at right angles to the bars *a a'*, but of a set of other bars, *c c*, arranged obliquely with respect to the said bars *a* and *b*, in manner as exhibited in the drawings, the whole being cast or formed in one piece, and with suitable guide and strengthening-flanges, as shown at *d d e f*. The guide-flanges or lips *d d* are to receive the guides *g*, through which the strings pass in going from the bridges to the straining-pins. These straining-pins, some of which are shown at *h h*, are to be inserted in the seats or extensions *i i* of the wooden back frame, such extensions resting directly against the edge of the iron frame A.

The sounding-board C, carrying the bridges *k l*, is first to be fitted to and held in place by the main iron frame. The auxiliary or hitch-pin frame or cap D is next to be placed over the sounding-board, at one of the lower corners thereof, in manner as shown in the drawings. The flanges or lips *m n* of the frame D lap on the edges of the main string-frame A, and serve to enable the main iron frame to support the auxiliary frame against the strain of the strings. The auxiliary frame I fasten to a ledge, *o*, projecting from the back frame. It may also be fixed to the main iron frame by screws.

The strings, hitched on pins projecting from the auxiliary frame D, extend over the bridges, and through the guides to the straining-pins. By my improved arrangement of parts, the main metallic string-frame is disposed between the back frame and the sounding-board, and not in front of the latter, as heretofore. The main iron frame also laps on the upper and lower edges of the sounding-board, the part so lapping on the upper edge of the sounding-board being the portion, D, for receiving the guides. Thus, the bars of the string-frame do not interfere with or come between any of the strings, and, by the sounding-board, are kept wholly out of sight from the front of the piano.

I make no claim to an iron frame formed to receive the sounding-board between two series of bars, so that, while one series may be in rear of the said board, the other shall be on its front, and extend between the strings,

the same being as shown and described in the United States patent, No. 55,385. My invention differs very materially therefrom, as I employ no such metallic frame, but make use of a wooden back frame, and employ no bars to extend across the sounding-board and between the strings. I also employ, with the iron frame, arranged between the sounding-board and the wooden back frame, a separate metallic plate, D, provided with flanges, to rest against the two adjacent edges of the metallic frame, the plate D being to support the hitch-pins of the strings.

What, therefore, I claim as my invention or improvement, is—

The combination of the wooden back frame B, the sounding-board C, and flanged plate D, with a separate metallic frame, A, arranged between the back frame and sounding-board, and made with flanges, to support the latter, and having no metallic bars or auxiliary frame to extend between the strings, the whole being substantially as described.

GEO. W. NEILL.
